UNITED STATES PATENT OFFICE.

CHARLES B. VAN HORN, OF DETROIT, MICHIGAN.

FLUID COMPRESSOR.

1,415,852.

Specification of Letters Patent.

Patented May 9, 1922.

Application filed June 30, 1919. Serial No. 307,609.

To all whom it may concern:

Be it known that I, CHARLES B. VAN HORN, a citizen of the United States of America, residing at Detroit, in the county

5 of Wayne and State of Michigan, have invented certain new and useful Improvements in Fluid Compressors, of which the following is a specification, reference being had therein to the accompanying drawings.

10 This invention relates to fluid pumps or compressors and more particularly to mechanism for operating the pistons thereof. The object of the invention is to reduce side thrust of the connecting rods upon the pistons and to so connect the cranks of two 15 pistons that the power of both cranks will be applied to each working stroke of each piston, thus applying load to each crank throughout its rotation and reducing vibration and consequent noise and wear.

20 A further object is to provide a construction having certain other new and useful features, all as hereinafter more fully described.

25 With these and other ends in view, the invention consists in the matters hereinafter set forth, and more particularly pointed out in the appended claims, reference being had to the drawings in which—

30 Figure 1 is a longitudinal vertical section through a device illustrative of an application of the invention, and

35 Fig. 2 is a transverse vertical section through the same, substantially upon the line II—II of Fig. 1.

It is the usual practice to connect pistons to their cranks by continuous connecting rods but such connection puts a heavy side thrust on the pistons, due to the angular movement 40 of the connecting rods relative to the plane of movement of the pistons. This side thrust causes the pistons and cylinders to wear and causes vibration, and one of the objects of this invention is to provide a construction wherein that portion of the connecting rod which is connected to its piston, will move substantially in the vertical plane of the axis of the piston and which mechanism for operating a pair of pistons, will 45 connect the cranks for such pistons in such a manner that the power of both cranks will be applied for operating each piston in both directions of its reciprocating movement.

50 In the drawing, a pump construction particularly adapted for creating fluid pressures

in small refrigerating apparatuses is shown, which pump is provided with a pair of cylinders and pistons therein operated by mechanism embodying the invention.

While a particular pump construction is 60 shown, it will be understood that the invention may be applied to other constructions and to other devices having cylinders and pistons therein operated by cranks. It will therefore be understood that the construction 65 and arrangement shown is merely illustrative of the invention.

In the drawing, 1 indicates a suitable crank case and 2 a pair of cylinders arranged in parallelism and spaced relation, 70 said cylinders being formed integral with or otherwise secured to the top of the crank case 1. In the cylinders are pistons 3 of any suitable construction and mounted in suitable bearings in the crank case, are crank 75 shafts 4, each having a crank 5 which is connected to the piston by a connecting rod and pitman, each connecting rod being pivotally attached at its upper end to the piston in any suitable manner, as by a pin 7 and the pitman 8 being attached to its crank by the usual bearing 9 or in any other suitable manner. The adjacent ends of the connecting rod and pitman are pivotally attached to one end of a rocker bar 10 which is supported intermediate its ends by a fixed pivotal support 11 mounted in any suitable manner in the upper part of the crank case.

The connecting rods 6 are pivotally attached as at 12 to the ends of the rocker, said 90 pivots being located in the plane of the axis of the pivotal support 11 for the rocker and each end of the rocker is preferably formed with a downwardly extending arm or offset 13 to which the upper ends of the pitmen 8 are pivotally attached by the pivots 14, the plane passing through the axes of these pivots being below the plane passing through the axis of the pivots 12 and the pivotal support 11. It has been found by experiment 95 that the various elements will function properly when the distance between the axes of the crank shafts 4—4 is the same as the distance between the centers of the pivots 12, the distance in each case being four times the 100 total throw of the crank 5. The axis of the pivotal support 11 lies at a distance from the plane passing through the axes of the crank shafts 4—4 equal to five times the total throw 105 of the crank. It is in a plane at right angles 110

to the plane of the axes 4—4 and midway between them. The distance from the center of the pivot 12 to the center of the pivot 14 is three-fourths the total throw of the 5 crank. Variations from these proportions will result in binding at the pivotal connections or total inoperativeness.

Power may be applied to the crank shafts 4 to simultaneously turn the same in opposite directions, in any suitable manner and the cranks of these crank shafts are arranged in opposed relation so that when one piston is up the other is down, thus giving a balanced reciprocating motion to the two pistons. 10

As shown, suitable means is provided for supplying power to the crank shafts and driving the same at a reduced speed from the speed of the driving shaft, said crank 20 shafts being preferably in the form of two parallel gears 15 spaced apart and connected by the crank or wrist pin 5, the gears having axial integral stubs forming the ends of the crank shaft, which ends engage suitable 25 bearings in the sides of the crank case. Upon a suitable intermediate shaft 16, extending across the crank case, is mounted a pinion 17 in mesh with the gears 15 of the two crank shafts and on this shaft 16 is also secured a 30 gear 18 which is in mesh with a pinion 19 on the driving shaft 20 which extends into the casing through a suitable bearing 21 on the side wall thereof. A train of reduction 35 gearing is thus provided for turning the crank shafts simultaneously in opposite directions and at a speed which is much less than the speed of the driving shaft.

The two connecting rods for the pair of pistons are connected by the rocker bar 40 which is pivotally supported midway between the vertical transverse planes of the two cylinders and power will be applied by both cranks equally to rock the rocker bar. In a single acting pump construction, the 45 suction or down-stroke requires but little power while the up-stroke compresses the fluid and requires an amount of power depending upon the compression produced. There is, therefore, a practically idle stroke 50 for each piston and by connecting the pistons up through the medium of the rocker bar, the power required for the compression stroke of each piston will be supplied by both cranks and therefore resistance to the 55 turning movement of both cranks will be continuous and not intermittent as where each crank is separately connected to its piston. Vibration and consequent wear is therefore greatly reduced by thus connecting up by means of a rocker bar, the connecting rods of a pair of pistons. Furthermore, in a gas compression system, the gas 60 flows in a closed circuit, and returns to the pump with considerable pressure. The gas 65 at the intake valve exerts pressure on the

piston as it is drawn into the cylinder. When the pistons are operated by connecting rods attached to a rocker bar, this pressure of the incoming gas is utilized to assist in the compression of the gas in the other 70 cylinder, which causes a balancing of pressures that aids in the smooth running of the machine, besides reducing the power required. The upper members 6 of the connecting rods being pivotally connected to 75 the ends of the rocker bar in the plane of the axis of the pivot, upon turning movement of the rocker for reciprocating the pistons in opposite directions, the lower ends of these parts of the connecting rods 80 will swing laterally to only a slight degree due to the large arc which the pivots 12 describe about the axis 11, and the upper ends of the parts 8 of the connecting rods are given a lateral swinging movement by being 85 connected to the rocker bar at a point below the plane of the pivots 11 and 12 so that the angular thrust of these lower end portions will not be excessive due to their short length and dead centers are eliminated. A compressor constructed as described has proved to be remarkably free from vibration and very noiseless in its operation. The power required being so efficiently applied, a smaller motor can be used 90 than is customary in similar mechanisms hitherto employed.

The construction provides a very simple and compact construction particularly adapted as a compressor for small refrigerating plants and in which the reduction gearing is all enclosed within the crank case free from dust and dirt and where it may run in oil to prevent noise and wear. Obviously, changes may be made in the construction and arrangement of parts within the scope of the appended claims and I do not, therefore, limit myself to the particular arrangement shown.

Having thus fully described my invention, what I claim is:

1. The combination of a pair of cylinders, pistons in said cylinders, a pair of cranks for operating the pistons, connecting rods and pitmen for connecting the cranks with 115 the pistons, and a member pivotally supported intermediate the axes of the two cylinders with its ends forming a pivotal connection between said rods and pitmen.

2. The combination of a pair of cylinders, pistons in said cylinders, a pair of cranks for operating the pistons, a pair of connecting rods, a pair of pitmen and a member pivotally supported intermediate its 120 ends and to the ends of which the adjacent ends of the connecting rods and pitmen are pivotally attached.

3. The combination of a pair of cylinders spaced apart and in parallel relation, pistons in the cylinders, cranks for operat- 130

- ing the pistons, a connecting rod and a pitman for connecting each crank with its piston, and a rocker bar pivotally supported intermediate its ends and forming at each end 5 a pivotal connection between a connecting rod and a pitman.
4. The combination of a pair of cylinders spaced apart and in parallel relation, pistons in said cylinders, cranks for operating the pistons, a connecting rod and a pitman connecting each crank with its piston, and a rocker bar pivotally supported intermediate its ends with the connecting rods, pivotally attached to the ends of said 10 15 rocker bar in the plane of the axis of its pivotal support and the pitmen pivotally attached to the ends of said rocker bar at points distant from the points of the pivotal attachment of the connecting rods thereto.
- 20 5. The combination of a pair of vertically disposed cylinders spaced apart and in parallel relation, pistons in said cylinders, cranks for operating the pistons, a connecting rod and a pitman for connecting each 25 30 crank with its piston, and a rocker bar pivotally supported intermediate its ends and to the ends of which the adjacent ends of the rods and pitmen are pivotally attached, the axis of the pivotal attachment of the connecting rods to the ends of said rocker bar being in the plane of the axis of the pivotal support of said bar and the plane of the axis of the pivotal attachment of the pitmen to said bar, being below and at a distance from said plane passing

through the axis of the pivotal support of said bar.

6. The combination of a crank case, vertically extending cylinders on said crank case, pistons in said cylinders, cranks for operating the pistons mounted in the crank case, connecting rods and pitmen connecting the cranks to the pistons, a rocker bar pivotally supported intermediate its ends upon the crank case and to the ends of which the adjacent ends of the connecting rods and pitmen are pivotally attached, and gearing within the crank case for imparting simultaneous rotation to said cranks. 40 45

7. The combination of a crank case, vertically extending parallel spaced cylinders on the crank case, pistons in the cylinders, cranks in the crank case, connecting rods and pitmen connecting the cranks and pistons, a rocker bar pivotally supported intermediate its ends upon the crank case with the adjacent ends of the connecting rods and pitmen pivotally attached to the ends of the rocker bar, a drive shaft extending into the crank case between the vertical 50 55 60 planes of the axis of the cranks and gearing within the crank case for transmitting simultaneous rotation to the cranks at a reduction of speed.

In testimony whereof I affix my signature 65 in the presence of two witnesses.

CHARLES B. VAN HORN.
